H. NEUWIRTH ET AL

HEATER FOR SHAPING EYEGlass FRAMES

Filed Dec. 13, 1923

Patented Aug. 18, 1925.

1,550,386

UNITED STATES PATENT OFFICE.

HERMAN NEUWIRTH AND JACOB BERNSTEIN, OF BROOKLYN, NEW YORK.

HEATER FOR SHAPING EYEGLASS FRAMES.

Application filed December 13, 1923. Serial No. 680,315.

To all whom it may concern:

Be it known that we, HERMAN NEUWIRTH and JACOB BERNSTEIN, citizens of the United States, and residents of the borough of Brooklyn, in the city and State of New York, have jointly invented certain new and useful Improvements in Heaters for Shaping Eyeglass Frames, of which the following is a specification.

10 It is common practice for opticians to reshape or re-size spectacle frames of the composition type, made of celluloid or similar material, in order to make the apertures in the frame fit some particular lens. Devices 15 have been made for heating and shaping, or sizing, these frames and our present invention relates to devices of this character. One object of our invention is to provide means for utilizing the heat generated by the heating element, which latter is of the electrical type, so that the heat is used in a most efficient manner and the major portion of this heat is concentrated upon the conical mandrel on which the eye glass frame is heated 20 and shaped. For this purpose we use a reflector arranged below the source of heat and in such position that it concentrates the heat on the inner surface of the conical mandrel. Another object of our invention is to prevent, as far as possible, the heat from passing down to the base of the device in order 25 that the base may be handled without burning the hands and in order that the heat will not reach the desk or table on which the device is placed. Our invention is adapted to be used with electrical means for heating, and the heating unit may consist of resistance wire mounted on a suitable support or it may consist of an incandescent lamp, both 30 forms being illustrated in the drawing.

In the drawing forming part of this application,

Figure 1 is an elevation of our improved device,

45 Figure 2 is a vertical sectional view taken on the line 2—2 of Figure 1 showing an incandescent lamp as the heating member.

Figure 3 is a similar view showing resistance wire mounted on a support as the heating member, and

50 Figure 4 is a diagrammatic view illustrating the reflecting action of the reflector.

In the drawing, we have shown a base 1 which may be made of metal or other material and it is preferably made quite heavy to

prevent the device from tipping over easily; and on the bottom of this base are arranged feet 2 of nonconducting material, such as fibre. The cable 3, connected with any source of electrical supply such as a lighting circuit, leads into the base at 4 and is connected with the heating member as will be hereinafter explained. Upon the top surface of the base 1 there is arranged a plate 5 of heat insulating material such as a pad of asbestos, and secured upon this pad is the lower member 6 of the heating device. This is shown in the general form of a bell although the shape may be varied as desired; and we have shown a series of apertures 7 in the lower portion of this bell for the purpose of permitting heat within the bell to escape and to permit cool air to enter in order that the bell may be maintained at a low enough temperature to permit it to be handled without burning the hands. Extending upwardly from the upper portion of this bell there is a conical shaped mandrel 8 and as a guide for determining the sizes to which the spectacle frames are expanded we have shown a series of lines 9 around the outside of this mandrel, together with numerals 10 indicating the diameter of the mandrel at these several lines. Near the top of the mandrel there is an inwardly extending flange 11 slightly below the top edge of the mandrel and if desired a removable cover 12 may be seated on this flange to close the top of the mandrel and retain most of the heat therein. In certain classes of work it may be desirable to remove this cover and to hold a portion of the spectacle frame over the open end of the mandrel to subject it to the heat flowing out of this open end. In most cases where the frame is being re-shaped or re-sized at the lens openings the cover 12 will be seated on the flange 11 as shown in Figures 2 and 3.

The conical mandrel is hollow so that it forms a heat chamber 13 wherein the heat generated by the heating member is applied to the inner surface of the mandrel. In Figure 2 we have shown an ordinary lamp socket 14 attached to the base 1 by means of screws 15 and resting on the pad 5. This socket, which it will be understood is connected in the ordinary manner with the wires of the cable 3, is adapted to receive the base of an incandescent lamp 16 so that the lamp when screwed in place extends 105

vertically above the socket and within the bell shaped member 6. When the current in the circuit is turned on heat is generated by this lamp and it passes upwardly within the 5 chamber 13 where it heats the mandrel. There is a tendency, however, for some of the heat to pass downwardly away from the mandrel and if this were permitted not only would there be a substantial loss of heat but 10 the base would become over-heated and this is prevented by the novel arrangement herein shown. For this purpose we have arranged a reflector 17 resting upon the socket 14 and extending upwardly around the lamp 15 16 to the bottom edge of the conical mandrel 8. While this reflector may take any desired shape we have found that the shape illustrated diagrammatically in Figure 4 will secure the most efficient reflection of 20 the heat upon the inner surface of the mandrel. In Figure 4 we have shown the action of this reflector upon the heat generated by the incandescent lamp. Assuming the center of the generation of heat to be at the 25 point 18 the heat waves striking the surface of the reflector will be reflected in the manner indicated by the arrows. It will be apparent that most of the heat which would otherwise pass downwardly to the base is 30 reflected upwardly and against the inner surface in the mandrel 8. Only approximately ten per cent of the heat will be reflected at such an angle as to strike the cover 12 or to pass out directly in case the cover 35 is not used. With the reflector thus arranged, most of the heat generated by the heating member passes up directly from the latter to the mandrel or is reflected thereby by the reflector, so that a maximum heating 40 effect upon the mandrel is obtained with any given heating member.

In Figure 3 we have illustrated a heating member consisting of a sheet 19 of mica having apertures 20 therein and resistance 45 wire in the form of a continuous coil 21 is threaded through these apertures and over the top edge of the sheet of mica, the terminals of this coil of wire being connected to the plug members 22, fastened to the lower 50 edge of the mica sheet. These plug members are adapted to slide over the contact members 23 which are bolted to the insulating plates 24 arranged above and below the bottom of the reflector; the plates 24 being held 55 in position by screws 25 entering the base 1. The wires of the cable 3 are connected to the lower ends of these contact members 23. The operation of this form of heater will be the same or similar to the action of 60 the lamp in Figure 2 except for the known difference between this form of heater and the lamp. The action of the reflector will correspond with the action of the reflector in Figure 2 and except for the form of the 65 heater and the method of mounting it the

device is otherwise the same as that shown in Figure 2.

In using the heater it is placed on the desk, table or other support and the spectacle frame is positioned over the mandrel 70 so that the latter passes through the lens opening of the spectacle frame and the latter is then placed downwardly on the mandrel. The frame is subjected to the heating action of the mandrel and if it is pressed lightly downwardly the frame will be expanded and when the frame reaches one of the gauge lines 9 it will have been expanded sufficiently 75 to receive some particular size of lens; after which the frame is removed and it may be dipped in water to harden it. This operation is repeated for the other lens member of the spectacle frame.

Having described our invention what we claim is:

1. A device of the character described including a base, a hollow, conical mandrel arranged on the base, a heating member arranged to heat the interior of said mandrel and a reflector arranged below the heating member and adapted to reflect the heat rays therefrom upwardly and against the inner surface of said mandrel.

2. A device of the class described comprising a base, a hollow, conical mandrel and means for supporting the mandrel on the base, said mandrel having an open lower end and a heating member mounted below said open end of the mandrel, and a reflector surrounding said heating member below the mandrel and adapted to reflect the heat rays from said heating member upwardly and against the inner surface of said mandrel.

3. A device of the class described comprising a base, a hollow, conical mandrel and means for supporting the mandrel on the base, said mandrel having an open lower end, a heating member mounted below said open end of the mandrel, and a reflector surrounding said heating member below the mandrel and adapted to reflect the heat rays from said heating member upwardly and against the inner surface of said mandrel, said mandrel and said reflector forming a chamber enclosing the heating member.

4. A device of the class described comprising a base, a hollow, conical mandrel and means for supporting the mandrel on the base, said mandrel having open ends, a heating member mounted below the lower end of the mandrel, a reflector surrounding said heating member below the mandrel and adapted to reflect the heat rays from said heating member upwardly and against the inner surface of said mandrel, and a cover 125 for the upper end of said mandrel.

Signed at the city, county and State of New York, this 21st day of November, 1923.

HERMAN NEUWIRTH.
JACOB BERNSTEIN.
